Fig. 1.

Fig. 2.

Fig. 3.

FIG. 1 is a front view of the parking meter showing my new design;

FIG. 2 is a rear view of the same; and

FIG. 3 is one side view of the parking meter, the other side being identical therewith.

In the figures the standard is shown broken away to represent indeterminate length.

The essential features of my design reside in the portions shown in full lines.

I claim:

The ornamental design for a parking meter, as shown and described.
